Des No 2324

Amos Rank's Design for a Wheel.

Fig. 1 Patented May 22, 1866

Q.S. 2324

Amos Brunk, of Salem, Ohio.

Letters Patent No. 2324, Dated May 22, 1866.

Design for the wheel of a Harvesting Machine.

The schedule referred to in these Letters Patent and making part of the same.

To all whom it may concern:

Be it known that I, Amos Brunk, of Salem in the County of Lumbiana, and State of Ohio, have invented and designed a new Wheel for Harvesting Machines, and I do hereby declare that the following is a full, clear, and exact description thereof reference being had to the accompanying drawings, making a part of this specification in which,

Figure 1, is a view of the outside of the wheel with its center piece removed.

Figure 2, is an outside view of the center piece.

Figure 3, is an edge view of the wheel.

Similar letters of reference indicate corresponding parts in the three figures. The design consists in having the spokes a, a, of the wheel radiate from a central hub b, surrounding which and concentric with it is a ring c with two rounded projections d, d, arranged diametrically opposite each other.

The outer ends of the spokes a, a, terminate at circumference of the wheel which is a narrow band or having a web c surrounding its inner side.

The hub b and the space enclosed by the concentric ring c is covered by a rosette or circular convey cap A which is shown in figures 2 and 3.

2

Des. 2324

The principal part of my design consists in the concentric ring C with
connected to a number of radial spokes, in conjunction with a circum-
ferential band or tire d and an interior web, which present both in an
edge and front view a handsome appearance as shown in the
drawings.

What I claim as my invention and desire to se-
cure by Letters Patent is the design for a wheel as shown and
described.

Witness,

R. H. Garrison
Chas. O. Davis
